PRESSURE RELEASEING VALVE FOR TEST
PIPES

Harry H. Crooke, Jr., Taft, Calif.

Application January 4, 1951, Serial No. 204,458

3 Claims. (Cl. 166—1)

1

The present invention relates to improvements in pressure releasing valves for test pipes and is of the type to be used to release the lower hole pressure of an oil well for testing purposes, after the casing packer has been set and expanded.

An object of the present invention is to provide an improved releasing valve for connection with a test pipe whereby the pressure of the bottom hole normally urges the releasing valve to closed position for preventing flow through the pipe members to the surface of the well.

A further object of the present invention is to provide a means for unseating the release valve from engagement with the valve seat between the pipe member and tubular casing and wherein a valve cage is disposed below the release valve for receiving the valve upon unseating movement thereof.

A further object of the present invention is to provide a piston valve reciprocably engaged in the lower pipe member and tubular casing whereby the bottom hole pressure will be exerted against the piston valve for urging the same upwardly and increasing the pressure in the chamber within the tubular casing.

Still another object of the present invention is to insert the metering disk between the piston valve and the releasing valve whereby the upward movement of the piston valve will be limited by the flow of fluid through the openings in the metering valve disk.

A still further object of the present invention resides in the provision of a tubular element having a partition wall formed at an intermediate portion thereof for preventing communication therethrough and wherein the walls of the tubular element are formed with openings both above and below the partition wall, the lower openings providing communication between the bottom hole and the underside of the piston for normally urging the piston upwardly whereby the holes in the upper walls of the tubular element will be sequentially uncovered in response to upward movement of the piston valve.

Various other objects and advantages will become apparent from the detailed description to follow. The best form in which I contemplated applying my invention is clearly illustrated in the accompanying drawings, wherein:

Figure 1 is a vertical transverse sectional view taken substantially along the longitudinal axis of the test pipe;

Figure 2 is a view similar to Figure 1 but wherein the release valve has been downwardly urged in response to the means for unseating the re-

2

lease valve and wherein the piston valve has been moved upwardly in response to pressure of the bottom hole, thereby uncovering openings in the walls of the tubular element for providing flow through the test pipe to the surface of the well;

Figure 3 is a horizontal transverse sectional view taken substantially along the plane of the line 3—3 of Figure 1;

Figure 4 is a horizontal transverse sectional view taken substantially along the plane of line 4—4 of Figure 1; and

Figure 5 is a horizontal detail sectional view taken substantially on the plane of line 5—5 of Figure 1.

Referring more particularly to the drawings, wherein like numerals designate like parts throughout, the numeral 10 designates generally the well casing in which the test pipe 12 is positioned. The test pipe 12 includes pressure valve means 14, a metering disk 16 and piston valve means 18.

The test pipe string 12 is comprised of a first pipe member 20 having a reduced diameter portion 22, the reduced diameter portion being tapered and externally threaded, a tubular casing 24 axially aligned with the first pipe 20 and threadably secured thereto by a complementary threaded bore 26. A second pipe member 28 is threadedly inserted into the lower internally tapered and threaded bore 30 of the tubular casing 24.

The first pipe member 20 is formed with a first bore 32 and a second tapered bore in communication therewith and providing a valve seat 34. A valve cage 36 is threadably supported by the lower end of the first pipe member 20 and has a plurality of apertures 38 formed therein to provide communication between the tapered bore forming the valve seat 34 of the first pipe member 20 and the exterior of the valve cage 36.

The pressure valve means 14 is comprised of a valve member 42 having an upper tapered seating portion 44 and a lower tapered nose portion 46. The upper tapered portion 44 is grooved at 48 for receiving a sealing ring 50 whereby when the valve 42 is in its uppermost position, the sealing ring 50 will be engaged against the valve seat 34 for sealing purposes.

The upper end of the valve member 42 is a reduced axially extending portion 52 which is disposed in the bore 32 when the valve is in its uppermost position.

The means for unseating the valve member 42 is comprised of the elongated rod 54 having spring guides 56 peripherally secured thereto for en-

gagement with the walls of the bore 32 for longitudinal guiding movement. The lower end of the rod 54 is engageable with the reduced axially extending portion 52 of the valve member 42 whereby downward movement of the valve rod 54 will 5 unseat the valve 42 from the valve seat 34.

The lower end of the tubular casing 24 is formed with a groove at 58 for seating the metering disk 16 therein, the upper end of the second pipe member 28 being in abutment therewith for fixedly supporting the metering disk 16. The metering disk 16 is formed with at least one metering aperture 62 for restricting the flow there-through. The metering disk 16 is also formed with an enlarged opening 64 with a sealing ring 66 seated within the inner periphery thereof. If desired, the cage 36 can be omitted and the metering disk 16 made integral with the casing 24.

The lower second pipe member 28 is formed with an enlarged bore 68 for reciprocably guiding the piston valve means 18, and a second reduced diameter bore 70 in communication with the bottom hole.

The bore 70 is internally threaded at 72 and a tubular element 74 has its lower end threadedly engaged therein. The tubular element 74 is formed with a longitudinally extending bore 76 with a partition wall 78 dividing the bore 76 into an upper portion 80 and a lower portion 82. The walls of the tubular element 74 are apertured below the partition wall 78 at 84 and above the partition wall at 86. The apertures 86 are upwardly staggered for a purpose to be hereinafter described.

The piston valve means 18 is comprised of a piston disk portion 88 having a sealing ring seal 90 peripherally formed thereon for sealing engagement with the walls of the bore 68. The piston disk portion 88 has axially extending thereto from the tubular portion 92 which is reciprocably guided on the tubular element 74.

The upper end of the tubular portion 92 of the piston valve means 18 is engaged in the opening 64 and is in sealing engagement with the sealing ring 66 and a sealing ring 94 carried externally of said tubular element 74 in alignment with the metering disk 16.

In view of the foregoing description, taken in conjunction with the drawings, it is believed that one skilled in the art will readily understand the manner in which the releasing valve and associated means operate. When it is desired to provide communication between the bottom hole and the bore 32 of the first pipe member 20, the rod 54 is downwardly urged for engagement against the upper end of the valve member 42. Of course, until the rod 54 is downwardly urged, the valve 42 is maintained in sealing engagement with the valve seat 34 by means of the pressure within the chamber 11 of the tubular casing 24, the pressure in the chamber 11 being maintained by the bottom hole pressure against the piston valve means 18.

As soon as the valve 42 has been unseated, it will be received in the casing 36 to prevent further downward movement thereof. Communication will thereby be afforded between the chamber 11 and the interior of the valve cage 36 and also through the valve seat or body to the bore 32 of the pipe member 20.

Upon release of the pressure within the chamber 11, the valve piston means 18 will move upwardly in response to pressure from the bottom hole through the apertures 84. The flow of fluid

from behind the piston disk 88 will be restricted through the aperture or apertures 62 in the metering disk 16. As the piston valve means 18 moves upwardly, the openings 86 in the tubular element 74 will be sequentially in communication with the bottom hole, thereby providing communication between the bottom hole and the chamber 11 and thence to the bore 32 of the pipe member 20. Thus, the flow through the test pipe will be effectively controlled by the metering disk 16 and will gradually increase in response to upward movement of the piston valve means 18 and covering the openings 86.

Having described the invention, what is claimed as new is:

1. A valve for pipe strings comprising a pipe member, a threaded projection on the lower end of said pipe member, an internally threaded tubular casing threaded on said pipe member, the bores of the tubular casing and pipe member being in communication with each other, the bore in the lower end of the pipe member downwardly diverging to form a valve seat, a tapered valve normally located within said valve seat, said valve having a seal ring mounted in an annular groove, said seal member providing a tight seal with the valve seat, means disposable within said pipe string for unseating said valve.

2. A valve for pipe strings comprising a pipe member, threaded projection on the lower end of said pipe member, an internally threaded tubular casing threaded on said pipe member, the bores of the tubular casing and pipe member being in communication with each other, the bore in the lower end of the pipe member downwardly diverging to form a valve seat, a tapered valve normally located within said valve seat, said valve having a seal ring mounted in an annular groove, said seal member providing a tight seal with the valve seat, means disposable within said pipe string for unseating said valve, the lower end of the threaded projection extending into said casing, a valve cage threaded onto the lower end of said threaded projection and locking said casing to said pipe member, said valve being receivable within said cage upon unseating movement.

3. A valve for pipe strings comprising a first pipe member, a tubular casing secured to the lower end of said first pipe member, bores of the tubular casing and first pipe member being in communication with each other through an opening formed by a valve seat between the casing and first pipe member, a valve member engageable with said valve seat, means for unseating said valve member, a second pipe member secured to said tubular casing and communicating with the bore thereof, and a piston member mounted in said second pipe member, the bore of said casing forming a fluid chamber, said piston member projecting into and being reciprocably positioned within said fluid chamber in sealed relation with a peripheral wall of said fluid chamber, said fluid chamber being communicated with the exterior of said second pipe member by a bore through said second pipe member and including an enlarged bore in said second pipe member, the pressure at the bottom of an oil well hole upwardly urging said piston member for increasing the pressure in said chamber, thereby normally urging said valve member into engagement with said seat when the casing and pipe members are lowered in the oil well hole, a tubular element having an intermediate portion thereof closed by a partition wall to prevent communication therethrough, said tubular element being fixedly secured to said sec-

ond pipe member, said piston member being reciprocably received on said tubular element, a portion of said tubular element on one side of said partition wall having openings formed in the wall thereof to provide communication between the bores of said second pipe member and the underside of said piston valve means for urging the same upwardly, and a portion of said tubular element above said partition wall having staggered openings formed in the wall thereof sequentially uncovered by upward movement of 10 said piston member.
